STEAM GENERATING SYSTEM

Jay Gould Coutant, New York, N. Y.

Application November 7, 1938, Serial No. 239,305
In France November 12, 1937

8 Claims. (Cl. 122—356)

This invention relates to steam generating systems, such for example as are used for industrial, central station and motive power purposes. This system while particularly adapted for the generation of vapors for the production of light, heat and power, may be employed to supply steam for refining or cracking, chemical and other processes.

Such systems commonly comprise an extended series of water circulation tubes exposed to the heat of the furnace or combustion chamber, with one or more receiving drums containing steam above water and one or more pumps for forcing water recirculation out from the drum and up through the tubes and back to the drum.

Important features of economic value in such systems are the means for obtaining high rates of heat liberation, together with great density of heat radiating particles per unit of furnace volume, and simultaneously therewith, high rates of heat absorption per unit area per hour for generator, economizer and air heater surfaces. Another valuable factor lies in causing a very rapid release of dry vapors per unit volume of the water and steam drum.

It is an object of the present invention to attain these features to a high degree, and to afford an apparatus with a low heat storage capacity, which consequently can meet and adjust itself to fluctuating demands for vapors with rapid response. This invention incidentally provides an excellent opportunity for saving of space and building structure and weight, resulting in low investment cost of apparatus or generator, and maximum overall economy in operating cost.

An important object and advantage of this invention is the burning of fuel at high rates of combustion at flame temperatures higher than the theoretical temperatures calculated from the constituents of the combustion, thereby providing the maximum intensity of radiant heat passing from the incandescent particles suspended in the gaseous products of combustion to the generator tubes. With this invention the generator or circulation tubes are of relatively small diameter, and the thickness of the tubes is reduced to a minimum so as not to retard or diminish unduly the amount of radiant heat utilized, thus reducing resistance to the conduction of the heat through the tube to the convecting or heat-conveying fluid or water in circulation, which is later vaporized in the generator drum.

The heat-absorbing or conveying medium in circulation is herein maintained under a pressure and a temperature greater than the pressure and

temperature existing in the generator drum, as will be further described. This prevents pockets or voids in the fluid, due either to eddy currents in circulation, or due to bubbles and spheroidal state in evaporation. Thus the tubes can not become overheated by reason of the inside surfaces not being wetted and cooled. Also there is prevented evaporation within the tubes and consequently there will be no incrustation or scale formation. The heat at the tube surface is communicated to the circulating fluid, superheating it say 38° C. to 75° C. superheat. Further, being maintained, as stated, under pressure greater than that in the generator drum wherein the vapor from the fluid is liberated, this develops additional temperature, 16° C. more or less, to the temperature of the circulating medium. The excess heat thus contained in the circulation medium, on reaching the drum space, flashes a part of the liquid into vapor.

Another object or feature of the invention, co-operating for more rapid steam liberation and heat exchange, by the increase of velocity of combustion and of intensity and density of surfaces emitting radiant heat, per unit of furnace volume, is the use of preheated air at more than 278° C., which use increases the flame temperature beyond the theoretical temperature based on the normal constituents of the burning fuel.

Therefore, the combustion is caused to take place, by this invention, in a positive atmosphere where the pressure is greater than atmospheric pressure by at least 1 kg. per sq. cm. above zero, and may be as high as 5 kgs.; such a pressure in the furnace compresses the number of radiant particles into a smaller space, with closer distribution, consequently increasing the amount of emitting surface per unit of furnace volume, with a resulting slight increase in temperature, which is enhanced because of reduction in time of fuel burning. By these features the amount of heat received by direct furnace and generator heating surface is much increased.

Further, the distance between suspended particles being reduced, the flame has less distance to travel, and the velocity of combustion is greatly increased. The heat transfer from flame to tubes is at a maximum. To utilize these conditions, it is the purpose of this invention to provide a heat-conveying fluid circulation system for properly carrying away the intense heat and cooling the tubes. At first glance this purpose may seem unnecessary because one naturally thinks of ordinary pulverized fuel furnaces with flame temperatures below the fusion point of the

ash, or about 1,320° C., corresponding to a radiant heat absorption of 150,000 calories per square meter per hour. The new economical fuels, such as a colloidal fuel composed of 40% fuel oil, 55% pulverized fuel, and 5% catalyzing radiant substance for aiding completion of the combustion with less excess air and at the same time raising the fusion point of the ash in the coal, may produce furnace temperatures 120° C. higher than fuel oil alone; while with preheated air, the furnace may attain in the neighborhood of 1,900° C., corresponding to a radiant heat absorption of 460,000 calories per square meter per hour. The weight of metal per square meter of generator heating surface and the amount of water in the tubes need then be but a fraction of the usual case, for example, in the neighborhood of one-twelfth, consequently the heat storage capacity of the unit in that case would be reduced proportionally, and meet fluctuating demands twelve times quicker.

Another feature of the invention is the use of relatively small steam drums, made possible because large water storage is not necessary to supply the aforesaid small diameter furnace and generator tubes. Large drum volume for steam liberation is not necessary, since this invention circulates and delivers the superheated, circulating water as a liquid, under pressure, and it is released to flash into steam in the drum space, with means relatively to increase the vapor liberating surfaces.

A particular object hereof is the delivery of the superheated liquid to the drum at substantially constant and uniform velocity above the water line, into the steam space, and preferably in an atomized condition. A supplemental object is the substantially uniform collection of vapor from the full length of the drum space, thereby to eliminate the longitudinal racing therein of vapor and consequently to eliminate entrained moisture, in the outgoing steam.

Another object is to dry further the vapor as follows. The feed water or infed fluid may be delivered over a series of chains through which the rising steam passes, thus serving as a washing apparatus for removing moisture from the vapor, while the chains being free to swing, are self cleaning.

Another useful feature and object of the invention is in the use of a blow-off collector pipe placed low within the steam-and-water drum, this being possible since the water is in a calm state, which allows for the precipitation of sediment, which may be removed from time to time through this blow-off collector pipe.

An object is to improve operation by the recirculation of water from and back to the drum at a very high rate, preferably at least or more than ten times greater than the steam output by weight, this recirculation being through small tubes, as already stated. The high velocity and large quantity of liquid circulated, without allowing evaporation in the small tubes, permits the use of untreated or raw water if necessary, while in emergency operation even salt water may be used.

An object of the low heat storage generator units described is to eliminate substantial time and heat losses in the generator operation whenever starting and stopping; further to allow quick cooling in case of need of repairs, a large unit being cooled in about an hour sufficiently to allow workmen to go inside; also that the generator may be put into service from cold condition to

full steaming capacity, in a few minutes, comparable to the fact that low heat storage capacity steam turbines may be put into full service within two to five minutes from cold condition.

The features and objects of this invention, in actual service, can reduce the relative heating surface area more than 10 per cent more or less as compared with usual or natural circulation boilers operating at pressures up to 100 kg. per sq. cm.; and the weight of a generator unit complete, and its space in a building, may be as low as 10 to 12 per cent of that of a modern power plant boiler and 15 to 20 per cent of a marine unit.

These various described objects and features will be better understood by referring to the accompanying drawings, of which

Fig. 1 which is a vertical cross-section view of a large generator or unit suitable for instance for supplying more than 50 tons of steam per hour.

Fig. 1^a, on a relatively enlarged scale, is an interior elevation view of a part of the wall of the overhead drum showing two of the nozzles or orifices delivering from the generator tubes into the drum.

Fig. 1^b is a diagrammatic sectional view of the automatic pump control valve indicated in Fig. 1.

Fig. 2 is a sectional elevation, on a still larger scale, of one form of restricted discharge nozzle or orifice for delivering from the tube system into the drum with release of pressure; and Figs. 3 and 4 are similar views of other forms of delivery restriction means or nozzles.

Fig. 5 is a vertical section view, on the same scale as Fig. 1, taken on the section line 5—5 of Fig. 1, showing substantially all of the interior elements within the drum.

Fig. 6 shows in section a portion of the length of one of the water tubes, provided with an interior device or whirling means which may be variously located along the length of the tubes.

Fig. 7 in similar section view shows a water whirling device or means adapted to constitute a restriction at the discharge of the tube and to impose a whirling motion on the delivered water.

The disclosed generator is preferably operated in a room in which the air is under a pressure greater than outside atmospheric pressure, and which may be several times as great, even as high as 5 kgs. per sq. cm. or more. By this method combustion takes place under a pressure greater than atmospheric pressure, which is 1 kg. per sq. cm. absolute, which elevated pressure compresses the heat radiating particles perhaps 80 per cent nearer to one another, the distance between them being only 20 per cent more or less of normal. It is obvious the flame propagation, velocity of combustion, rate of fuel burning, completeness of combustion will be very greatly increased. This reduces the time factor, and consequently the losses from slow combustion will be reduced. This in turn results in higher temperatures and greater intensity of the radiant heat emission from the flame. The generator is preferably built with gas-tight casing, and the combustion air along with the fuel is injected into the furnace under such pressure as to cause the same conditions within the generator setting, which is to be considered as covered by this invention.

Referring first to the main elements of the steam generator hereof, it comprises the combustion chamber, which may be sectional, comprising in the illustrated case three furnace

chambers 4, 4 and 4 separated by division walls 3 and all delivering into a general space or furnace chamber 4^a above the sectional chambers. All of these chambers are enclosed within an exterior metal casing which has a refractory floor 1^a and refractory linings or firebrick walls 2 around the sides of the furnace. All of the combustion spaces deliver eventually to flues 2^a extending upwardly and out at the top of the generator, and eventually to a stack.

An overhead drum 9 is shown, representative of one or more high drums, into which the generator tubes deliver. The drum may be described as a steam-and-water drum, having a steam space 6^a above the water space 6, with a water line 26 between, to be maintained substantially steady. For this purpose the water infeed pipes 7, supplying water to offset the consumption of steam, are assumed to be controlled by any usual boiler feed regulator, not shown, adapted to maintain the water level lower than the orifice outlets 16 but higher than the water outlet pipe 10 to be referred to. At the top the drum has the usual steam outlet 29 extending to the place of consumption. The drum 9 is shut off or shielded from the direct heat of the combustion by a refractory housing wall 9^a extending under the drum and upwardly to the walls of the flues 2^a.

While the drum 9 has been described as an overhead drum it is not intended to restrict it to a drum of high location in relation to the tubes, the important thing being that the drum should be substantially higher than the pump. The tubes, receiving from the pump, might even trend downwardly through the chamber to a low drum, so long as the pump is still lower than the drum. The drum is relatively small, and may be from 25 to 50 per cent less in volume than ordinary drums as used for similar outputs of steam of the same degree of dryness.

By this invention rapid recirculation of the generator water is maintained, and the circulation system may be described as follows. The water collector pipe 10 within the drum has perforation 10^a so as to receive water from the full length of the drum. From one end of the water collector extends, at a downward slant, toward the left, a downtake pipe 11 which extends first to the intake of a force pump 12 driven by a motor 12^a and is continued downwardly at 13 to the low point of the circulation system at which is a series of headers 14 interconnected by pipes 13^b. The motor 12^a may be energized through a conventional motor controller 12^b from line wires 12^c. From the other end of the water collector, extending at a downward slant, is a right-hand downtake 23 leading to a force pump 22, in this case turbine-driven, and delivering to a downtake extension 13^a which at that side delivers into the low header system 14. It is advantageous to incorporate in each of the downtakes 11 and 23 a check valve 25 or 24, permitting downflow but preventing return upflow of the circulating liquid.

The circulation system is completed by the water or generator tubes 5, taking off from the low headers 14, and extending upwardly through the combustion chambers 4, preferably along the walls 2 and 3 and eventually delivering into the drum after passing through a tortuous configuration in the chamber 4^a as shown by the bent tube portions 15, occupying the upper combustion space. The high ends of the generator tubes pass from the combustion space to the

drum, the tubes separately entering the drum so as to deliver transversely into the steam space thereof, above the water line 26.

As already stated the flow in the tubes may be reversed, if the drum is at a low point. The tubes are preferably of quite small size compared to standard boiler tubes, for example $\frac{3}{4}$ inch in diameter more or less, the tube wall being of steel of a thickness of $\frac{1}{16}$ inch more or less depending on the pressures used.

It is an essential characteristic of this invention that the several water tubes, delivering into the steam-and-water drum throughout its length are provided with restriction means, of any suitable kind adapted to impede the flow, such as the restriction orifices 16 shown separately in several forms in Figs. 2, 3 and 4. On delivery of the heater water thus into the drum, the impact thereof is preferably taken by a series of baffle strips 27, causing unevaporated water to descend into the water space, a substantial fraction of the water however being converted or flashed into steam and passing into the steam space of the drum. The liquid water therefore passes through the closed circuit consisting of the drum, the water collector pipe, the downtakes leading to the low headers, the force pumps associated with said downtakes, and the uptakes or generator tubes exposed to the combustion heat and delivering back, through the restricted orifices 16 into the drum. The result of the described combination is that, beyond the force pump, and throughout the length of the generator tubes, up to their delivery orifices, the hot circulation water remains in liquid condition and under a temperature and pressure substantially higher than those existing within the drum. The tubes therefore carry only liquid medium or water, and there is no steam formation within them, the water only evaporating upon passing through the restriction devices into the lower pressure prevailing within the drum.

Taking a specific example, the drum pressure may be about 400 lbs. per sq. in. absolute while that beyond the pump up to the tube delivery orifices may be boosted by the pump to about 420 lbs., these pressures corresponding to steam temperatures of about 445° and 449° F. respectively. The higher pressure water is progressively heated in each of the tubes nearly to the orifice, but does not break into steam until passing the orifice into the drum, this being prevented by the high pressure developed by the pump with the aid of the restriction, these elements being designed and operated for the conditions prevailing in the system. On entering the drum, part of the superheated water breaks into steam with the drop in pressure, taking heat from the balance of the water for this result, the unevaporated water descending to the water space for recirculation. The orifice restrictions are the controlling factors, and the several orifices may be differentially constructed or adjusted for consistent results. Thus the tubes 5^a, having a greater extent of heat exposure than tubes 5, would tend to develop higher temperatures before discharge and therefore more readily incur evaporation unless the restriction be less and the water flow faster. Consequently the orifices 16^a of tubes 5^a are made larger, as shown in Fig. 1^a, than the orifices 16 of tubes 5, allowing a greater weight of water to pass per second, and thus avoiding the formation of steam ahead of the orifice. This differential showing of the two orifices in Fig. 1^a is considerably exaggerated, in

order to show the principle, and the actual differences in orifice diameters will not usually be as great as indicated in this figure. In any case the orifices are calculated to deliver a predetermined rate of liquid at the existing predetermined pressure.

This being the general plan and operation of the present invention the various elements and details will now be further described.

The generator setting preferably has an air tight casing 1, insulated from the fire by insulating refractories, or low-heat storage capacity or cellular firebrick 2. Similar refractories form the shatterproof division walls 3 between the multiple furnaces 4. Because of the high rates of fuel consumption, possibly only in such relative small furnaces, the temperature, density of combustion, and intensity of radiant heat are exceedingly high. The walls are protected by reason of their lining with the water tubes 5.

These tubes 5 have their metal walls so thin as not to retard appreciably the conduction of the heat which is received by radiation, the heat being quickly transferred to the cooling and conveying liquid within, and then passing to the drum by convection. The liquid or water is supplied to the drum by regulated feed pumps, not shown. The water preferably sprayed into the drum by the feed pipes 7, and is showered upon a free swinging series of small baffle chains 8, from which it drops into the relatively calm water pool in the drum. The heat conveying medium or water flows thence under steam generator pressure and temperature into the collector pipe 10, perforated to collect water uniformly from along the whole length of the drum 9. The water flows by gravity through the downtake pipes 11 and 23 to the driven pumps 12 and 22 which discharge at a pressure, for example, 1.3 kgs. per sq. cm. greater than the generator pressure. This pressure is maintained in the circulating water in pipes 13 and the headers 14 that supply the radiant heat absorbing tubes 5 which are in series circuit with the convection heat absorbing tube banks 15 leading to the orifices 45 which discharge into the drum.

Fig. 2 shows a special construction of restriction orifice 16, the tube being inserted and expanded in a perforation of the drum 9 in usual manner but extending beyond the inside face, and this interior end being swaged, rolled or contracted to form the orifice 16. A preferred orifice construction is shown in Fig. 3, in which the tube 5 has its end extending inside, in which an annular metal block or ring 17 is fixed, this having a threaded hole to receive a removable orifice piece 18, which therefore is interchangeable as to size of orifice. An orifice or restriction device of convenient construction is that shown in Fig. 4 wherein the orifice piece 16^b is a simple apertured disk. In this construction a short pipe length or nipple 17^b is fitted permanently to the drum wall, this and the tube end 5 having welded flanges 17^c between which the orifice piece is clamped by means of exterior bolts 18^b. Instead of a simple apertured orifice the throttling or restriction of flow from each tube into the drum may be effected otherwise, as by means of a multitude of small perforations constituting a spray nozzle, or a porous body through which the liquid must pass into the steam space, or a movable device or vane obstructing free discharge. In any case the outflow from the tube is preferably throttled to afford a uniform delivery from each of the tubes, or a predetermined 75

weight of water per hour, the restriction at the same time cooperating and maintaining the desired elevated pressure within the tubes 5 and their bent portions 15.

Fuel oil, colloidal fuel, or other fluid fuel is supplied to a series of burners 19, for example, in the furnace front wall, for delivery into the combustion chamber sections 4, 4, 4. The fuel is ignited with the combustion supporting air, preferably under elevated pressure, in the chambers 4. The combustion may be at moderate temperatures at first; following which the hot gases in the usual manner may pass through an air preheater (not shown) and excessively heat the air, the air being delivered to the burners 19, which gradually increases the temperature and pressure in chamber 4.

In the meanwhile steam has been generated by evaporation in drum 9, creating high pressure, and part of the steam flows by a pipe 20 to a steam throttle valve 21, which, when opened, supplies steam to the pressure-controlled turbine-driven pump 22. The drum water flows through pipe 23 and through its check valve 24 into the pump 22, which discharges by pipe 13^a to headers 14. The pressure-controlled steam turbine and pump maintains a uniform water pressure in the circulation system, at say 3 kgs. per sq. cm. greater than that in the steam drum.

The pressure-combustion supporting air entering the furnace at high temperature and pressure with the fuel, causes temperatures and radiant heat intensities to be developed superior to present practise. This intense heat is transferred by radiation, conduction and convection to the cooling and heat conveying liquid or water which is under pressure in the tubes 5. The water, being superheated, flows through the tubes 5, tube banks 15 and discharges through the orifices 16, located either inside or outside of drum, and at points above the water line in drum in such manner that the main body of the water remains relatively calm. From each orifice 16 the water is atomized by impact against baffles 27, whereupon the small particles of water escaping from the higher pressure and superheated temperature give up their excess pressure and superheat by being partly converted to saturated vapor, or steam. The water due to the sudden drop of pressure causes a rain which actually washes the vapor. The vapor rises toward the self cleaning chains 8, where it is again washed by the incoming feed water from pipe 7; and is then collected uniformly, transversely of the drum by the steam collector or dry pipe 28 that delivers to steam outlet 29.

Unlike usual boilers this invention permits the removal of the sediment by a sludge blow-off consisting of a pipe 30 located in the bottom of the drum; this pipe being slotted or perforated uniformly to collect mud or settling from the lowest part of the overhead drum; in contrast to blowing off at the lowest point of the circulation, as is common with natural circulation boilers. Fig. 1 shows a shield or plate 30^a in the drum, above the blow-off pipe, to protect the settling operation. From one or both ends of the pipe 30 is a sludge downtake pipe containing a blow-off cock 30^b.

As the liquid in circulation in the tubes, for absorption and entrainment of heat, is maintained under pressure considerably higher than the pressure in the generator drum, this results in an increased capacity for entrainment of heat per kilogram of liquid in circulation, which re-

duces the necessary volume and diameter of the tubes and of the generator drum itself; and this allows the metal to receive and transmit more heat because of the elimination of the known phenomenon which obstruct the transmission of heat by convection to the liquid in circulation, as occurring with natural circulation of the liquid.

As the tubes 5, in which circulates the liquid for absorption and for entrainment of heat under pressure and at high temperatures, pass into the generator drum above the water level, a part of the liquid is vaporized by the excess heat without effecting the calm state and temperature of the main body of liquid stored in the drum, so that the level does not tend to rise and fall with the increase and decrease rate of fuel burning or steam output, and this allows the use of relatively small generator drums.

The tubes 5 for the absorption and for entrainment of heat are preferably exteriorly accessible at or near their ends, for permitting quick repairs, in the case where a tube explodes or develops leaks, without putting the generator out of service. This is shown in Fig. 1, where at the left side each tube 5 may be reached near its bottom end at the header 14, also at its upper end near the drum. For example a powerful implement may pinch and seal the defective tube at these two points, without interrupting operations.

The following further considerations apply to the disclosed embodiment of the invention. As stated, the generator or water tubes are as thin-walled as is consistent with safety. There are indeed no thick metal parts at any point which are exposed to excessive fluctuations of temperature. Within the tube system described, substantially uniform temperatures of circulating fluid are maintained at each specific location. Because of this, temperature variations in metal parts are minimized, which substantially eliminates caustic embrittlement and fatigue of metal, especially under corrosion.

An advantage of the described invention is that when the generator is out of service, for example one generator among many in a station, it is practicable to have the generator stand by, ready for resumption of service, without possibility of damage even in cold weather; it being only necessary to stop the operation of the recirculation pump, maintaining a pilot fire for low heat and allowing the water to circulate in the system by natural or unforced flow.

Referring further to structure, the bent tube system 15 is shown suspended by means of depending hangers 15^a, from which extend horizontal cross members 32, preferably hollow for circulation of cooling fluid; the pipes 15 passing around the members 32 in two or more tiers, as shown, separated by spacers 15^b. The reinforcement bars 31 in the partition walls 3 may also be hollow, constituting pipes for fluid circulation, for their protection and that of the wall.

Referring further to the force pump, this is to be controlled from the inlet and delivery sides of the pump, by any suitable type of governor or control device, so as to maintain a predetermined pump pressure at the orifices. This has reference to a predetermined pressure difference, the pump elevating the pressure by a predetermined amount, as in pounds per square inch, and the pressure dropping by the same amount on traversing the orifices. The orifices are calculated so as to deliver a predetermined rate of liquid at such predetermined pressures.

A conventional means to maintain the desired elevated pressure beyond the force pumps 12 and 22 and up to the orifices 16 is indicated at the righthand side of Fig. 1 and in Fig. 1^b. Since both pumps deliver recirculated water into the same system of exposed tubes 5, the desired control may be at both sides or either side to maintain a predetermined recirculation pressure, above the pressure existing in the drum 9. Such a control is shown at the righthand side of Fig. 1 where there is indicated a steam turbine 22^a which drives the centrifugal pump 22 that applies forced pressure to the recirculated water. The turbine is fed by steam, received from the drum through the tube 20, containing a hand throttle or cut-off valve 21. For automatic recirculation pressure control there is shown, also interposed in the pipe 20, a special control valve 40 adapted to open or throttle more or less the steam passing to and operating the turbine, under the control of the elevated water pressure in the downtake 13^a beyond the pump.

The valve 40 is shown in a conventional form in Fig. 1^b. Its movable member or gate 41 is carried on a stem 42, these sliding through the valve for the adjustment of steam flow from the upper to the lower part of the steam pipe 20. The valve gate 41 is adjustable slidingly through a guideway 43, so that its tapered end may approach more or less the valve seat 44, through which the steam flows from the first to the second part of the pipe 20. The parts 43 and 44 are fixed or integral with the valve casing 45, to one side of which is attached an arched cover or cap 46, the casing and cap forming a control chamber. As a typical pressure responsive means, between the valve casing and cap is clamped a diaphragm 47, to which the valve stem 42 is attached, so that diaphragm movements shift the valve. In a conventional way, the diaphragm and stem movements may be controlled or biased by a resilient means or helical spring 48, shown applied to the stem, as at one end, and adjustably confined by a threaded hand wheel or nut 49 fixed on the threaded end of the stem by a lock nut 49^a. The spring 48 is confined between the adjusted wheel 49 and an outer fixed thrust bracket 48^a; and the adjustment should be such that, through the compression of the spring, tending to open the valve, the valve operates in accordance with the existing conditions and requirements, taking into account the head of water between drum and pump, and other factors, to afford the desired control.

The diaphragm 47 divides the valve chamber into a low pressure compartment 50 and a high pressure compartment 51. The drum pressure is communicated to the chamber 50 by a passage 52 in an interior wall of the valve, this pressure therefore being substantially the same as the pressure of the water passing from the drum to the pump through pipe 23, Fig. 1. The high pressure of the water beyond the pump is communicated back to the chamber 51 by a pilot passage or tube 53, tapped into the downtake 13^a and extended upwardly and through the wall of the arched cap of the valve.

By this described arrangement, when the delivered water pressure in the downtakes 13^a and 13 and the exposed tubes 5 tends to drop to a relative pressure where vaporization might occur, the lowered pressure is communicated through the pilot tube 53 to the valve chamber 51, causing the diaphragm and the valve gate to recede under the counterpressure of the chamber 50,

the wider opening of the valve thus admitting more steam to the turbine, so that the greater force and speed of the turbine and pump automatically correct and restore the predetermined delivered pressure. When the delivery pressure has risen to the predetermined relative pressure, above the boiler and drum pressure, the diaphragm will have moved inward, further closing the valve and compressing the spring, until the adjustment is such that the turbine will tend to maintain the desired relative pumped pressure and so preclude vaporization in the system of exposed water tubes of the generator. If both pumps are desired to be automatically controlled in the manner described, the delivered water pressure need merely be utilized also to adjust the electrical controller 12^b at the left analogously to the adjustment of the steam valve 40 at the right.

By the use of three or other plural number of combustion chamber sections 4, 4 and 4 the operation of the generator is made flexible, since any one or more of these sections may be put into or out of service, and each has its bounding walls lined with water tubes.

The water whirling device shown in Fig. 6 is illustrated as a twisted strip or helical vane 35, for the purposes to be described, and it may be located at any one or more places along the length of each tube or selected tubes. This device is in the nature of a steep-pitched screw, developed for example from a sheet metal strip, and its immediate effect is to impose a rapid rotation upon the advancing stream of water. The effect of this rotation is to create a powerful centrifugal force, and the operation of this force is to classify the advancing flow. The portions of the water which are colder, and therefore denser or heavier, are constantly thrown toward the periphery, into what may be considered as an outer zone X which is directly in contact with the metal wall of the tube 5. The classification may tend to produce an intermediate zone Y, while the central zone or core Z of advancing water is of the lowest density.

The effect of this improvement is that the flowing stream of water is able to receive and absorb heat from the tube wall with maximum rapidity and efficiency. In the operation of the present apparatus it is intended that the water flowing through the tubes has a minimum or inappreciable proportion of bubbles of air or gas; it is as solid as possible, and preferably superheated as already explained. This factor being eliminated it is manifest that the hottest water of the advancing stream tends to enter the central zone Z, while the coldest water, the most receptive to heat absorption, takes its proper place in contact with the tube wall. It is believed that there will be a constant interflow between the zones X, Y and Z as the relative temperatures and densities therein are altered by the absorption of heat.

By this branch of the present improvement therefore the heat of combustion, both radiant and convection heat, is received by the tubes, transferred to the water, and absorbed and carried away with maximum speed. Efficiency is enhanced because a substantially greater percentage of the combustion heat is absorbed into the flowing water, and the outgoing furnace gases will be proportionately less hot.

Stating in other words the advantageous effect of the operation of the whirling device 35, it renders substantially greater the mass-flow con-

tact of the advancing water with the wall of the tube, and as well the velocity-of-flow contact is greater, to the enhancement of general efficiency.

5 Referring to the modification shown in Fig. 7, it has already been stated that the restriction near the delivery of each tube may be by means other than an orifice, and Fig. 7 shows a restriction 36 in the form of a twisted vane analogous to that shown in Fig. 6, but preferably of much lower pitch. This device 36 impedes greatly the passage of water from the tube into the drum 9, because the fast advancing flow of the water is converted, by this fixed helix, into a very high state of rotation, the absorption of energy for this purpose affording the desired restricting effect.

20 An advantage of the form of restriction shown in Fig. 7 is that in delivering the hot water into the drum, the rapid whirling throws the water violently into a spray, even pulverizing it into a fine mist. The result of this is that the release of steam from the water is promoted to a maximum degree.

25 What is claimed is:

1. The method of operating a steam generator of the kind comprising a steam-and-water drum having a feedwater inlet and steam and water outlets and a bank of water tubes exposed to the combustion heat and connected for delivery into the steam space in the drum and a water pump arranged to force hot water recirculation from the drum water outlet back to and through the tubes; said method comprising substantially restricting the water flow by predetermined throttlings in the several tubes at a restriction point between the tube-heating zone and the delivery into the drum, while cooperatively operating the pump with control from its pressure side and in coordination with the flow restricting action to maintain in the tubes a water pressure predeterminedly elevated above the drum pressure sufficiently to preclude vaporization and flow acceleration in the tubes beyond the pump and up to the restriction point and to cause recirculation at a rate at least several times by weight of the steam consumption rate; whereby the recirculated water within the heating zone is maintained as a solid water column flowing at low velocity and therefore with optimum contact and capacity for high rate of heat absorption thus to become superheated in its liquid form at the elevated pumped pressure until upon release and delivery into the drum with substantial pressure drop the solid water flashes partly into outgoing steam and partly settles as water for forced recirculation; and whereby the fuel combustion in the generator may be maintained at a super rate accompanied by high intensity of heat generation affording high rate of heat transmission to the tubes and liquid water flowing therethrough and thereby affording super rate of steam generation.

60 2. The method of operating a steam generator of the kind having a steam-and-water drum and a feed-water inlet, the drum having water outlet and steam outlet, with a bank of water tubes exposed to the combustion heat and connected for delivery into the steam space above the water in the drum, and a force pump arranged to promote hot water recirculation from the drum water outlet back to the tubes; said method comprising restricting the tube water flow at a restriction point between the heat-absorbing zone and the delivery into the drum

while cooperatively operating the pump to maintain in the tubes a water pressure elevated sufficiently above the drum pressure to prevent appreciable vaporization or flow acceleration in advance of the restriction point; whereby the recirculated water is wholly liquid and therefore has capacity for high rate of heat absorption in the heating zone and so becomes superheated at the elevated pumped pressure and upon release and delivery into the drum flashes partly into steam for consumption and partly settles as water for forced recirculation; controlling the water force pump from its pressure side in a manner to maintain substantially a predetermined elevated pressure in the tubes up to the restriction point, with recirculation rate of not less than about ten times by weight of the steam consumption rate; and effecting the water flow restrictions through calibrated throttlings to afford a predetermined substantially constant recirculation rate at the elevated pumped pressure.

3. A steam generator comprising a steam-and-water drum having a steam outlet from the upper part drum steam space, consisting of a steam collector extending lengthwise of the drum with inlets along its length to receive steam transversely from the drum, a bank of water tubes arranged for absorption of combustion heat and for delivery into the steam space of the drum, a water recirculation passage extending from the drum water space back to the tubes, and a force pump operable in such passage to promote recirculation of water through the tubes and back to the drum; the same characterized in that said water tubes are provided with circulation restriction means located beyond the heat-absorption zone between such zone and the place of delivery into the drum above the water space therein, and that the deliveries thereof are in distributed arrangement along the length of the drum, and that said pump and restriction means are cooperative to maintain the circulating water in the tubes at a pressure substantially higher than that in the drum and thereby in the condition of solid water throughout the heat absorbing zone; whereby such water is caused to flow through said tubes without appreciable vaporization up to such restriction means while becoming superheated substantially above the temperature of the water in the drum, and thereupon beyond the heat-absorption zone to flash partly into steam within the steam space above the water in the drum; and thereby preventing bubbling of the steam through the water, minimizing water agitation, minimizing vapor flow lengthwise of the drum, and promoting steadiness of the water in the drum.

4. A steam generator comprising a steam-and-water drum having a low water outlet and a high steam outlet, a bank of water tubes exposed within the zone of radiant and convection heating in such generator and connected for delivery into the drum, a header connected for distributing water to said tubes, a water recirculation passage extending from the drum water outlet back to the header and tubes, and a water pump arranged and operable in such passage to force recirculation of water from the drum through such passage, the header and the tubes and back to the drum; said generator being characterized in that at the lowest part of the drum is a longitudinal sludge collector with means for discharging it for sludge blow-off pur-

poses, and a longitudinal wall immersed above and shielding the setting of sludge; and the said generator being further characterized in that said water tubes are provided with water flow restricting means located beyond such heating zone between such zone and the delivery into the drum, and that said pump and restricting means are cooperative to maintain the recirculating hot water in the tubes at a water pressure substantially higher than that in the drum sufficient to maintain it liquid throughout the heating zone; whereby such water is caused to flow through said tubes so solid water without vaporization up to such restricting means at the higher pressure while becoming superheated in the tubes substantially above the temperature of the water in the drum, and thereupon beyond the heating zone discharging into the lower pressure of the drum partially as steam and partially as water passing into the steam and water spaces respectively of the drum.

5. A steam generator comprising a steam-and-water drum having water infeed means and a steam outlet from the drum steam space, a bank of water tubes arranged for absorption of combustion heat and for delivery into the drum, a water recirculation passage extending from the drum water space back to the tubes, and a force pump operable in such passage to promote recirculation of water through the tubes and back to the drum; the same characterized in that said water tubes are provided with circulation restriction means located beyond the heat-absorption zone between such zone and the place of delivery into the drum, and that said pump and restriction means are cooperative to maintain the circulating water in the tubes at a pressure substantially higher than that in the drum and thereby in the condition of solid water throughout the heat absorption zone; whereby such water is caused to flow through said tubes without appreciable vaporization up to such restriction means while becoming superheated substantially above the temperature of the water in the drum, and thereupon beyond the heat-absorption zone to flash partly into steam within the drum; and characterized further in that at the lowest part of the drum is a sludge collector with means for discharging it for sludge blow-off purposes, and above said sludge collector a shield adapted to protect the settling of sludge, and thereabove a water collector extended longitudinally and delivering to the recirculation passage.

6. A steam generator comprising a steam-and-water drum having a low water outlet and a high steam outlet, a bank of water tubes exposed within the zone of radiant and convection heating in such generator and connected for delivery into the drum, a header connected for distributing water to said tube, a water recirculation passage extending from the drum water outlet back to the header and tubes, and a water pump arranged and operable in such passage to force recirculation of water from the drum through such passage, the header and the tubes and back to the drum; said generator being characterized in that the said water tubes are cylindrical and provided with interior water whirling devices adapted to impose rotation upon the solid water traversing the heat-absorption zone under forced recirculation and to divert centrifugally the heavier cooler portions of the water toward the tube walls while the lighter hotter portions flow centrally without vaporization, thereby enhancing the capacity of the flowing water to absorb

combustion heat and to become superheated as liquid before release and partial vaporization beyond the heat-absorption zone; and the said generator being further characterized in that said water tubes are provided with water flow restricting means located beyond such heating zone between such zone and the delivery into the drum, and that said pump and restricting means are cooperative to maintain the recirculating hot water in the tubes at a water pressure substantially higher than that in the drum sufficient to maintain it liquid throughout the heating zone; whereby such water is caused to flow through said tubes as solid water without vaporization up to such restricting means at the higher pressure while becoming superheated in the tubes substantially above the temperature of the water in the drum, and thereupon beyond the heating zone discharging into the lower pressure of the drum partially as steam and partially as water passing into the steam and water spaces respectively of the drum.

7. A steam generator comprising a steam-and-water drum having a low water outlet and a high steam outlet, a bank of water tubes exposed within the zone of radiant and convection heating in such generator and connected for delivery into the drum, a header connected for distributing water to said tubes, a water recirculation passage extending from the drum water outlet back to the header and tubes, and a water pump arranged and operable in such passage to force recirculation of water from the drum through such passage, the header and the tubes and back to the drum; said generator being characterized in that within the lower part of the drum is a longitudinal water collector extending substantially the length of the drum and with inlets along its length adapted to receive water from the drum and deliver it into the recirculation passage leading to the pump, and in that the combustion chamber is divided into subchambers each extending parallel with the drum and each having circulation tubes, with means to put part or all of the subchambers into or out of service to adjust operation to varying output requirements; and the said generator being further characterized in that said water tubes are provided with water flow restricting means

located beyond such heating zone between such zone and the delivery into the drum, and that said pump and restricting means are cooperative to maintain the recirculating hot water in the tubes at a water pressure substantially higher than that in the drum sufficient to maintain it liquid throughout the heating zone; whereby such water is caused to flow through said tubes as solid water without vaporization up to such restricting means at the higher pressure while becoming superheated in the tubes substantially above the temperature of the water in the drum, and thereupon beyond the heating zone discharging into the lower pressure of the drum partially as steam and partially as water passing into the steam and water spaces respectively of the drum.

8. A steam generator comprising a steam-and-water drum having water infeed means and a steam outlet from the drum steam space, a bank of water tubes arranged for absorption of combustion heat and for delivery into the drum, a water recirculation passage extending from the drum water space back to the tubes, and a force pump operable in such passage to promote recirculation of water through the tubes and back to the drum; the same characterized in that said water tubes are provided with circulation restriction means located beyond the heat-absorption zone between such zone and the place of delivery into the drum, and that said pump and restriction means are cooperative to maintain the circulating water in the tubes at a pressure substantially higher than that in the drum and thereby in the condition of solid water throughout the heat absorption zone; whereby such water is caused to flow through said tubes without appreciable vaporization up to such restriction means while becoming superheated substantially above the temperature of the water in the drum, and thereupon beyond the heat-absorption zone to flash partly into steam within the drum; and characterized further in that its combustion chamber is partitioned into a plural number of subchambers, with burners in each, and with the walls of each lined with circulation tubes; whereby one or more or all of said subchambers may be put into or out of service to adjust the generator operation to the vapor output requirements.

JAY GOULD COUTANT.
